UNITED STATES PATENT OFFICE.

CARL E. FRITZSCHE, OF FORT FAIRFIELD, MAINE.

ICE-CREAM-CONE WRAPPER AND CARRIER.

Application filed August 4, 1926. Serial No. 127,071.

The handling and carrying of a number of filled ice cream cones is usually inconvenient and requires the application of both hands.

The present invention provides a wrapper 5 having a flat bottom, enclosing walls and a partition connected to opposite walls and having openings for receiving the cones, the parts being foldable into flattened form to admit of storing a number of the wrappers 10 in a pile.

While the drawings illustrate a preferred embodiment of the invention it is to be understood that in adapting the means to meet specific needs and requirements, the design 15 may be varied and such other changes in the minor details of construction may be resorted to within the scope of the invention as claimed, without departing from the spirit thereof.

For a full understanding of the invention and the merits thereof, reference is to be had 20 to the following description and the drawings hereto attached, in which,—

Figure 1 is a perspective view of an ice cream cone wrapper and carrier embodying the invention, showing the same in section and extended and supported in upright position upon the flat bottom,

Figure 2 is a sectional view, the dotted lines showing a number of cones in place, and

Figure 3 is a sectional view of the wrapper, as it appears when folded.

Corresponding and like parts are referred 35 to in the following description and designated in the several views of the drawings by like reference characters.

The combined wrapper and carrier comprises a flat bottom 1 and enclosing walls 2, 40 two of the walls being narrow and the other two wide. The flat bottom 1 is elongated, that is, narrow and of some considerable length, the narrow walls being at the ends of the bottom and the wide walls at the 45 sides thereof. The construction is such as to admit of the flat bottom 1 folding upwardly between the wide sides, as indicated most clearly in Figure 3, and the narrow

walls folding inwardly and in consequence, the wrapper is adapted to fold in flattened form, so that a number of the wrappers may 50 be arranged in a pile.

The partition 3 is located some distance from the flat bottom and is attached along its marginal edges to the side walls of the wrapper. This partition, when extended, parallels the bottom 1, as indicated most clearly in Figure 1, and it is of a less length than the bottom 1 to admit of the end walls of the wrapper folding inwardly. A plurality of 55 round openings 4 are formed in the partition 3 and are adapted to receive the pointed ends of cones 5, as indicated most clearly in Figure 2. The openings 4 are spaced apart a distance to admit of the upper ends of the cones touching without crowding. The marginal edge portions of the partition 3 are adhesively secured to the side walls of the wrapper by being pasted thereto. The body of the wrapper and the partition 3 consist 60 of paper, or other suitable material best adapted for the purpose. The wrapper, when extended, as shown in Figure 1, may be placed upon a flat surface, thereby holding the cones in upright position, which is 65 desirable at times, particularly when it is required to temporarily lay the package aside.

Having thus described the invention, I 70 claim:

A combined wrapper and carrier for ice cream cones, the same consisting of an elongated flat bottom, and enclosing walls, the bottom being foldable upwardly and the end walls foldable inwardly, and a partition having 75 its ends terminating short of the end walls of the wrapper to provide for the inward folding of said walls and attached along its marginal edges to the side walls of the wrapper, and provided in its length with 80 cone receiving openings, said partition being foldable intermediate its edges to lie between 85 the side walls of the wrapper.

In testimony whereof I affix my signature.

CARL E. FRITZSCHE. [L. S.]
